UNITED STATES PATENT OFFICE

93,916

DESIGN FOR A COMBINATION BOTTLE AND TRAY WITH GLASSES

Hugo Erickson, Chicago, Ill.

Application March 23, 1934, Serial No. 51,152

Term of patent 14 years

To all whom it may concern:

Be it known that I, HUGO ERICKSON, a citizen of the United States, residing at Chicago, in the county of Cook and State of Illinois, have invented a new, original, and ornamental Design for a Combination Bottle and Tray with Glasses, of which the following is a specification.

In the accompanying drawing:

Figure 1 is a plan view of the combined bottle and tray, with the glasses removed to show the configuration of the tray more clearly; and

Figure 2 is a side elevation with the glasses in place.

The parts are proportioned with the glasses of

a height and taper such that the rims of the glasses are set in a substantial distance from the edges of the tray, in plan view, the inset being substantially the same along the sides as at the bottom.

The corners of the bottle are not concentric with the adjacent glasses, and the top corners differ from the bottom corners. The tray face has a shallow transverse depression registering with each transverse row of glasses.

I claim:

The ornamental design for a combination bottle and tray with glasses, as shown and described.

HUGO ERICKSON.
